UNITED STATES PATENT OFFICE.

JAMES D. MATTISON, OF HOLYOKE, MASSACHUSETTS.

FORMING-MACHINE.

1,080,359.

Specification of Letters Patent.

Patented Dec. 2, 1913.

Application filed August 4, 1900. Serial No. 25,864.

To all whom it may concern:

Be it known that I, JAMES D. MATTISON, a citizen of the United States, residing at Holyoke, in the county of Hampden and State of Massachusetts, have invented certain new and useful Improvements in Forming-Machines, of which the following is a specification.

This invention relates to the class of machines for automatically forming articles in multiple and exactly alike, from a bar of metal or other material fed through a tubular spindle to the cutters or shaping tools.

In the machine as herein illustrated there are two spindles and two sets of cutters, which increases its capacity fourfold. The spindles are not superposed but disposed in a horizontal plane, so that the chips or cuttings from one mechanism will not fall on the other. The invention is not in all respects restricted however to this double construction or feature of the machine.

The novel features of the invention will be hereinafter described and carefully defined in the claims.

In the accompanying drawings, which illustrate an embodiment of the invention Figure 1 is substantially a vertical, longitudinal, section of the machine as a whole. Fig. 2 is substantially a vertical, transverse section taken at line x^2 in Fig. 1, looking toward the right; and Fig. 2^a is a detached view of the pawl-device for operating the gage-wheel. Fig. 3 is a side elevation of a cutter-carrier and its swinging support, being taken from the left of Fig. 2. Fig. 4 is an end-view of the cutter-carrier or cylinder; and Fig. 5 is a detached view of the device for intermittently rotating said cylinder. Fig. 6 includes two views of the bolt for locking said cylinder or cutter-carrier. Fig. 7 includes two views of the cam for operating the cutter-carrier and gage wheel. Fig. 8 is a detached view of the cross-head or yoke for operating the cutter-carriers and gage wheels. Fig. 9 is an end-view of the machine as seen from the left in Fig. 1, and showing the worm gearing. Fig. 10 is a vertical, axial section of the turret and turret-slide, illustrating the rotative operating mechanism. Figs. 11 and 12 each include two views of one of the clutch collars of the worm-wheel of the reducing gear; and Fig. 13 is a sectional view of this clutch device. Figs. 14, 15, 16 and 17 are detail views of the mechanism for operating the

turret-slide, Fig. 17 being a dissected plan view. Fig. 18 is a detail plan of the turret cam-drum and the clutch devices associated therewith; and Fig. 19 is a cross-section at x^{19} in Fig. 18. Fig. 20 is a plan of the parts seen in Fig. 18, and illustrates the operation of the clutch. Fig. 21 is a side view of the clutch devices for operating the cutter-carrier. Fig. 22 is an axial section of the cam-drum for operating the shipper and chuck, and of the friction box. Figs. 23, 24 and 25 are views illustrating the construction of the friction box. Figs. 26 to 29 are detail views of the means for feeding the stock through the tubular spindle and gripping it. Figs. 30 to 36, inclusive, are views illustrating the cutters and means for securing them. Fig. 30 is a sectional view of the ring cutters and their securing devices. Fig. 31 is a side elevation of same. Fig. 32 is an end view of the securing collet 82 at the left in Fig. 30. Fig. 33 is an end view of a coned ring collet which engages the cutter. Fig. 34 is an end view of the collet 83 seen at the right in Fig. 30. Fig. 35 is an end view of one form of ring cutter. Fig. 36 shows a split ring cutter and a collet 83 of reduced size. Fig. 37 is an enlarged view, in elevation, of the construction shown in Fig. 13. Fig. 38 is a vertical section, partly in elevation, showing a portion of the mechanism for effecting rapid and slow movements of the cutter carriers toward the work. Fig. 39 is a horizontal section, partly in elevation, of the mechanism shown in Fig. 38. Fig. 40 includes a face view and an edge view of the gears connecting shafts 7 and 48. The main sections of the machine are indicated as to position by capital letters. A indicates the position of the shipper and chuck mechanism for feeding the bar or stock to the cutters. B indicates the position of the cutters. C indicates the position of the turret mechanism. The operative parts are mounted in a suitable frame of any kind, which will not require description. 1 is a cone pulley to receive a belt for driving the machine forward, or in the normal direction, and 2 is a pulley to receive a belt for driving said pulley in the opposite direction to the pulley 1, for reversing. These pulleys are loose on a driving shaft 4, and either may be coupled to the shaft for driving it by means of a clutch 3. When the

clutch is moved to the right (in Fig. 1) the pulley 1 will be clutched to said shaft, and when moved to the left, the pulley 2 will be clutched thereto. The shaft 4 is hollow, and the clutch 3 is operated by a slide-rod 73 in the hollow of the shaft. The means for controlling the operation of this slide-rod will be described hereinafter. The shaft 4 drives two tubular spindles 5, rotatively mounted in the frame, through suitable gear wheels 6, seen at the left in Fig. 1, and in Fig. 9. These spindles are disposed in substantially horizontal plane, and not one above the other. The object of this is to prevent the cuttings or turnings from the stock in one spindle from falling down upon that below. The gear-wheels 6 drive a cam-shaft 7, through suitable change wheels 8, seen best in Fig. 9. This is the ordinary mechanism for effecting a change of speed and will be familiar to any skilled machinist.

The means for feeding and clutching the stock will now be described with especial reference to Figs. 1, 26, 27, 28 and 29. On the shaft 7 is mounted a cam-drum 9, the cams 9^a on which operate shifters 10 and 27, the former operating a gripping device for holding the stock (S in Fig. 28) while it is being operated on, and the latter operating a feeding device for feeding the stock forward to the cutters. The gripper device, best seen in Fig. 29, comprises a coned sleeve 11, slideable on an enlarged part of the spindle 5 and circumferentially grooved to receive a lug on the shifter 10. This sleeve, when moved to the left (in Fig. 29) acts on the longer arms of elbow-levers 11^a, fulcrumed in the spindle, to cause the shorter arms of said levers to act upon and push outward (to the right in Fig. 29) a slideable split clamping sleeve 13 in the spindle. The outer end of this sleeve is coned and plays in the coned nosing 5^a on the spindle, whereby a very slight endwise movement of the sleeve 13 causes it to grip on the stock it embraces and hold it fast. When the sleeve 11 is moved back (to the right in Fig. 29) springs 11^b retract the levers 11^a and the shorter arms of the latter which engage the gripping sleeve 13, draw back or retract the latter. Figs. 26, 27 and 28 illustrate the means for feeding the stock. Fig. 26 is an end view of the shifter 27, showing its adaptation to both spindles, and to the operation of both of the sliding collets or sleeves 28 on the spindles. This shifter 27, and the shifter 10, are slideable on a fixed rod or bar 12, in the frame, and the shifter 27 engages circumferential grooves in the respective sleeves 28. This shifter has a lug which is engaged by a cam 9^a to move the sleeve 28 to the right in Figs. 1, 27 and 28. This sleeve has pivotally mounted in it two oppositely disposed serrated jaws 29, which bear on and bite lightly into the stock S

when the sleeve is moved to the right for feeding, and which slide over the stock when the sleeve moves in the opposite direction. Each jaw has behind it, back of the fulcrum or pivot, a spring 29^a, tending to press the jaws up to the stock. These jaws play in slots in the tubular spindle. Figs. 26 and 27 illustrate the means for limiting the movement of the sleeve 28 toward the left, and Fig. 27 shows the spring 30^a, for returning the shifter 27. A screw 30 extends through the frame (at the left in Fig. 27,) and screws into the frame at the right. This screw has loosely embracing it the spring 30^a and it passes loosely through the shifters. On it is a collar 30^b which engages the shifter 27, whereby it forms a limiting stop to limit the extent of movement of the shifter 27, under the influence of the spring 30^a, and thus regulate the extent or length of each feeding movement of the sleeve 28. The head of this screw 30 projects and is squared to receive a wrench. The cam on the drum 9 operates the shifter 10 in both directions. As the cam-drum 9 rotates, at each rotation the cams 9^a thereon act to feed out the stock S to a predetermined extent, and to grip it and hold it while the cutters operate on it. The cams on the drum will be so disposed as to first feed the stock and then clamp it fast. When fed out to the point where the cutters operate, the stock is backed by a head 14 which prevents it from springing away from the cutters. This head has in it work-supports 15 in which the stock rotates, said supports being open on the side toward the cutters, as seen in Fig. 2.

The cutting mechanism will now be described, premising that in this machine the stock S rotates and the cutter or cutters are brought up to it by a swinging movement. In order, also, that several cutters may be brought up successively to work on the stock, these cutters are mounted in longitudinally extending chambers in the periphery of a cutter cylinder or carrier 19, which turns on an arbor 20^a, in a frame 20. Fig. 3 shows this carrier in side elevation, and in Fig. 4 it is seen in end elevation. The frame 20 rocks on a fulcrum 21 and is actuated to bring the cutter up to the stock by mechanism that will be hereinafter described. The carrier 19 may be rotated to bring any one of its cutters into position, but while the cutting is under way the carrier is locked against rotation by a lock-bolt 22, seen detached in Fig. 6, and in place in Fig. 2. This bolt is disposed upright in a recess in the frame 20, and is pressed upward by a spring seen in dotted lines in Fig. 2, into engagement with a locking recess 19^b in the carrier. The bolt is pressed down and disengaged by a cam 23^a on a rocking collar 23 on the same arbor with the carrier. This

collar, which is seen detached in Fig. 5, is rocked through a connecting-rod 24 coupled (at 24^a in Fig. 5) to said collar, and at its other or lower end to a cross-head 25 (seen 5 detached in Fig. 8) hung on the shaft 7, and actuated by a cam 26^b on said shaft. This cam is seen detached in Fig. 7. The collar 23 has on it a spring pawl 23^b (Fig. 5) which engages shoulders on a boss on the 10 carrier—one shoulder for each of the cutters in the carrier—and this pawl acts to rotate the carrier intermittently at the proper times and to the proper extent to bring a fresh cutter into play. A hook 23^c on the 15 collar takes under a roller stud (22^c in Fig. 6) and holds the lock-bolt against accidental depression and disengagement when it is in its locking position. It may be proper here to state that the cutter carrier 19 has (see 20 Fig. 3) a spring back-pawl, indicated at 54, which is a well known device, to prevent back rotation of the carrier. As has been stated the cross-head 25 is hung on and guided in its up and down movement on the 25 shaft 7, and it is also guided below on a boss on a shaft 48, to be hereinafter described. On the face of the cross-head 25 (Fig. 8) are two projections 25^a, 25^b and when the cam 26^b rotates (to the right as seen in Fig. 30 2) it first engages the projection 25^a catching under it and elevating the cross-head 25, thus throwing the pawl 23^b into the notch in the cutter carrier 19, while the cam 23^a, (Fig. 5,) depresses the stop bolt 22, freeing 35 the cutter carrier 19, so that as the cam 26^b continues to rotate to the right it catches on top of the lug 25^b, which is then in elevated position, and depresses it, carrying the cross head 25 downward and turning the cutter 40 carrier 19 one step.

The means for rocking the frames 20 about their fulcrums 21, in order to bring the cutters up to the stock, will now be described.

45 On the pendent portion of the respective frames 20 are hung hinged buffers 20^c, carrying rollers 20^b, adapted to be acted on by cams 26 and 26^a on shaft 48; and the extent or depth of the cut is regulated in each case 50 by a gage-wheel 86, rotatively mounted in the frame 20 and provided with radial and peripheral studs 86^a, which may be set in or out, and which are brought, successively, to bear on the back of the buffer 20^c and limit 55 its movement independently of the main frame. There are, as here shown, five of these studs 86^a, one for each cutter in the carrier 19, and they are brought successively into operative position behind the buffer 20^c 60 by the downward movement of the cross-head 25, through the medium of a connecting-rod 88 (Figs. 2 and 2^a) coupled at one end to a lug on the cross-head 25 and at the other end to a rocking pawl-carrier 53 (similar 65 to that seen in Fig. 5) which turns on a

boss in the gage-wheel 86 and carries a spring pawl 87 which engages teeth or shoulders on said boss. As the pawl-carrier is rocked, the pawl thereon imparts intermittent rotation to the gage-wheel.

The shaft 48 is called, for convenience, the slow shaft and the shaft 7 the rapid shaft, and their relative speed is variable. A worm or screw 49, drives the shaft 48 through a worm wheel 63 on the latter, this wheel being clutched to the shaft by a ratchet mechanism 62 of a known kind.

It is essential that the stock S shall be fed to the cutters at the proper time and at any time required. When, therefore, the piece 80 operated on requires the use of two cutters only in the cutter-carrier, the stock should be fed forward only at each two operations of the cutter-carrier. If, however, the article being made requires the use of three cutters 85 of the cutter-carrier, then the feeding device should operate but once at each three operations of the cutter-carrier. As there are, as here shown, five cutters in the cutter-carrier 19, the feeding mechanism for the 90 stock may be set to operate once for from one to five operations of the cutter-carrier. This regulation is effected by the means now to be described. The device for effecting 95 this regulation is called a friction box, and is indicated as a whole by D in Fig. 1; it is seen more in detail in Figs. 22, 23, 24 and 25. The fixed box 31, which incloses a part of the shaft 7, contains a friction cup 32, lined with leather and provided about its periphery with five series of notches 32^b, the first series containing five notches, the second four notches, the third three, the fourth two, and the fifth one. It may be stated here 100 that Fig. 23 is an edge view of the friction cup. This cup 32 is driven by a cone 33, on a sleeve 34, on the shaft 7. There is a pawl 35^a (Fig. 24) on the box 31, the nose of which is held in engagement, normally, with one of said notches. This pawl is thrown 105 out by a pin 26^c (Figs. 2 and 7) in the boss of the cam 26^b at each time the shaft 7 rotates, but drops into the next succeeding notch, thus locking the cup 32, while the cone 33 goes on and completes its rotation. It 110 may be explained here that the pin 26^c acts on an arm 35 (Figs. 24 and 25) on a rock-shaft 35^b, on which the pawl 35^a may be shifted along to put it in position to engage 115 any one of the five series of notches 32^b. It 120 is secured when thus adjusted and set, by a screw 35^c. The friction cup has on its end or bottom a projection or boss 32^a (seen in Fig. 23), and this cup will rotate but one 125 step while a sleeve 34 (which carries the cam 26^b) makes one complete rotation. If the pawl 35^a be set to engage that series containing five notches 32^b, for example, the pawl will lift and drop into the next succeeding notch and it will be seen from this 130

that it will require five complete rotations of the cone 33 to produce one complete rotation of the cup 32. Now as the latter, by its rotation, controls the feed of the stock, it will be seen also that there will be but one operation of the feed to five rotative impulses of the cutter-carriers.

The cup 32 controls the feed through the following described means: The drum 9, that carries the cams 9^a, effects the feeding of the stock, is loose on the shaft 7, and may be clutched thereto by a suitable clutch-device 9^b (Fig. 22), the clutch being set by pushing in (to the left in Fig. 22) a spring shifting bolt 37. As the cup 32 rotates the boss or projection 32^a thereon wipes over the inner end of a slide 36 in the frame and aligned with the shifter 37, and said slide pushes the shifter 37 in or back, thus causing the latter to set the clutch and connect the drum 9 to the shaft 7. One member of the clutch slides on the shaft 7 and is made to rotate therewith by a cross-pin 38 extending through a slot in the shaft. As soon as the drum 9 starts to rotate, the shifting bolt is carried around so that its end bears against the face of the machine frame and this holds the clutch set until the drum shall have made a complete rotation. The bolt 37 now registers with the bore in which the slide 36 plays and shoots into same, thus disengaging the clutch and locking the drum to the frame. This single rotation of the drum completes a feeding operation. While this feeding operation is being effected the cutter-carriers are being rotated so as to bring the proper cutter into position for the next operation.

The sleeve 34, carrying the cam 26^b, is operated and controlled by the mechanism now to be described with especial reference to Figs. 18, 19, 20 and 21. On the shaft 7, and forming a substantial continuation of the sleeve 34, is a sleeve 42. Splined and slidable on the shaft 7 is a double-faced clutch-member 39, one face of which may be made to engage a clutch-member 40 on the sleeve 42, and the other face with a clutch-member 41. When the sliding member 39, rotating with the shaft 7, engages the member 40, the sleeve 42 is driven; and in order that it may make but one rotation and then stop, the following described mechanism is employed: To operate the clutch-member 39, there is a spring bolt 43, mounted slidably in a cam-drum 44 on the shaft 7. This bolt, as the drum rotates, becomes operative to force back a slide 45, which forms a part of a shifter 46, which engages a circumferential groove in the member 39. Therefore the operation of the bolt 43 sets the clutch-member 39 into engagement with the member 40. There is a lug 46^a on the shifter 46, which lug engages a circumferential groove 42^a (Fig. 21) in the sleeve 42 and holds the clutch-

members 39 and 40 locked together until the rotation is completed; then the lug 46^a moves out into a wider portion of the groove 42^a and the clutch is automatically disengaged. This assures the stopping of the action of the friction device D, which controls the cam-drum 9, and the action of the cross-head 25, which controls the operations of the cutters and the gage-wheels 86. When the cutter-cylinders or carriers are required to make more than one movement, the bolt 43 is caused to retain its pressure on the shifter-slide 45 so that the shifter cannot disengage the clutch. The drum 44 is rotatable on the shaft 7 and is driven from a gear-wheel 47 fixed on the shaft 48, which rotates relatively slowly. Therefore, as the drum rotates quite slowly the end of the bolt 43 moves off from the end of the slide 45 before the rotation of the sleeve 42 is quite completed and thus allows the bolt with the shifter 46 to spring back into place. It will therefore be noted that when the bolt 43 is made to impinge upon the slide 45 far enough from its edge, it will still continue its pressure after one rotation of the sleeve 42 is completed and the clutch will remain engaged until the completion of a second rotation. If more than two rotations are required the bolt 43 is allowed to impinge sooner, and before the cam-drum shall have carried it off from the end of the slide 45, a third rotation of the sleeve 42 will have begun. The means employed for effecting the above object is best seen in Fig. 19. It consists of a collar 50, mounted loosely in a circumferential groove in the neck of the drum 44 and held elastically or yieldingly against rotation by a spring 51. When the bolt 43 is carried around to the upper part of the cam-drum it is pressed back by contact with a boss 52 on the frame (Fig. 18) and is thus in position to impinge upon a boss 78 on the collar 50 (Fig. 20). This collar then acts as a carrier for said bolt to the point where the latter is allowed to impinge on the end of the slide 45, and this point is determined by a pawl 55 which engages one of a series of teeth 50^a on the collar 50 and prevents the further rotation of the latter with the bolt 43. It may be explained that the frictional pressure of the bolt on the face of the collar carries the latter around with it, distending the spring 51, until the pawl 55 engages the teeth on the collar, after which the bolt slides off from the collar onto the slide 45 and sets the clutch. The extent of movement of the collar before its arrest by the pawl, depends on the point of engagement of the latter with the ratchet teeth 50^a, and this point of engagement is determined by a gage-wheel 56 back of or behind the pawl and having substantially the same form and functions as the gage-wheel 86.

before described. The amount of projection of the screws of the gage-wheel govern the number of rotations of the sleeve 42 without disengagement of the clutch. The member 41 of the clutch is connected with the drum 44, and if the clutch-member 39 be shifted so as to engage with this member 41, the drum will be driven with the shaft 7 and of course at the same speed. When driven in this manner the drum communicates its motion to the lower shaft 48, and through it to the cams 26 and 26^a, thereby rotating these cams rapidly and causing them to operate the cutters with greater rapidity. This accelerated movement of the normally slow shaft 48 is permitted by the ratchet mechanism 62 (Fig. 13) which will be of the known kind where the teeth will slip or wipe over each other when the driven clutch-member is made to travel faster than the other. The details of the ratchet mechanism in Fig. 13 are further illustrated in Figs. 11, 12, and 37. Suitably fixed to the sleeve 63^a of the gear or pinion 48^a is a toothed annulus or ring 62, shown in Fig. 12, which is keyed to the sleeve 63^a in any suitable manner, as by means of the key 62^b. Loosely surrounding the sleeve 63^a is a toothed annulus 62^a, shown in Fig. 11. The toothed annulus 62^a has a spline or feather connection with the worm wheel 63 by means such as the key 63^b. The annulus 62^a is forced yieldingly toward the annulus 62 by means such as a plurality of small coil springs 62^b set into sockets in the worm wheel 63, the construction being such that the worm wheel 63, through the ratchet mechanism consisting of the annulus 62 and the annulus 62^a, will normally rotate the sleeve 63^a, and through the gear wheels 48^c, 48^b, and 48^a, the shaft 48, at a slow speed, but when a fast speed is applied to said shaft 48 from its opposite end, the annulus 62^a will slip over the teeth of the annulus 62 in the well known manner of a ratchet, and will thus permit this temporary rapid rotation of the shaft 48.

Referring particularly to Figs. 18, 19, 20, and 21, the operation of the parts is substantially as follows: The upper shaft 7 rotates normally at a fast speed, and the lower shaft 48 rotates normally at a slower speed. The cam drum 44 is normally rotated at the same speed as the slow shaft 48 through the gear wheels 47, 47^a, and 44^b, connected with drum 44. The clutch 39 is splined or keyed on shaft 7 and is double faced so that it is adapted, when moved to the right in Fig. 21, to engage the clutch member 41 so as to rotate the drum 44 and the lower shaft 48 at the same speed as the shaft 7, and when moved to the left in Fig. 21, the clutch member 39 engages the member 40 and thus rotates the sleeve 42 which, through the mechanism described, operates or rotates the cutter car-

riers and also feeds the stock through the cam drum 9. It may be here explained that the reason why it is desirable at times to rotate the lower shaft 48 rapidly is, that said lower shaft, through the cams 26 thereon, is adapted to swing the cutter carrier frames 20 toward the work. It is desirable that these frames 20 shall be moved very rapidly until the cutters are nearly in contact with the work, and that said frames shall then be fed slowly forward to move the cutters into engagement with the work or stock. Therefore, when the clutch 39 in Fig. 21 is engaged with clutch 41, the lower shaft is rapidly rotated, to swing the frames 20 toward the work, and when said clutch 39 is moved out of engagement with 41, as hereafter described, the normal slow speed of the lower shaft 48 is resumed. In order to convey a clear understanding of this part of the invention, a description will now be given of the successive operations of the sleeve 42 which rotates the cutter carriers, and of the shaft 48 which swings the cutter carrier frames toward the stock. Referring to Figs. 18 and 20, it will be seen that as the drum 44 is slowly rotated in the direction of the arrow, the bolt 43, which is backed by a strong spring 43^c, engages an inclined projection 78 on collar 50 and rotates said collar slowly in the same direction as the drum 44. When one of the gear teeth 50^a in Fig. 19 on the collar 50, is engaged by the pawl 55, the collar 50 stops. The pin 43, however, continues its movement with the drum 44 until it slips off the inclined projection 78 of the collar 50 and strikes against the end of bolt 45 and forces the same to the left in Fig. 21. Connected with the bolt 45 is a shifter 46 having a lateral arm in engagement with the clutch 39. The bolt 43, therefore, through bolt 45 and shifter 46, moves the clutch 39 into engagement with clutch 40. As the arm 46^a on shifter 46 simultaneously moves out of the recess in the groove 42^a, and thus unlocks sleeve 42, which was previously locked against rotation by the arm 46^a, said sleeve 42 begins to rotate and thus operates the cutter carriers 19. If it be desired to rotate the sleeve 42 several times, the pawl 55 in Fig. 19 will be arranged so as to permit very little movement of the collar 50, for which reason the bolt 43 will quickly slip off of said collar 50 and engage the bolt 43, and as the drum 44 and bolt 43 are traveling at the slow motion of the lower shaft 48, the bolt 43 will remain in engagement with bolt 45, and consequently clutches 39 and 40 will be engaged, for a long enough time to give several rotations of the sleeve 42 during the time that the bolt 43 is traveling slowly across the end of bolt 45. When bolt 43 finally slips out of engagement with bolt 45, the spring 46^b in Fig. 21 will move the shifter 46 so as 130

to unclutch 39 from 40. Spring 46^b, however, can only unclutch the members 39 and 40 when the arm 46^a is opposite the recess in the groove 42^a, so that the sleeve 42 will 5 always stop its rotation and be locked in position at one particular point in its rotation. The operations just described will have operated the cutter carriers 19 to bring the proper cutters into position. The continued slow rotation of the drum 44 next 10 brings the bolt 43 into engagement with a small lever 61 for the purpose of transmitting rapid movement to the drum 44 and shaft 48 to feed the cutter carrier frames 15 20 rapidly toward the stock. The lever 61, as shown in Figs. 18, 38 and 39, is provided with gear teeth which mesh with rack teeth on a longitudinally movable rod 60. Rigidly fixed on rod 60 is a sleeve 60^a, which 20 is provided with a lateral extension 60', which fits around the bolt 45 in rear of the spring 46^b, so that as the lever 61 draws the rod 60 and sleeve 60^a to the right in Fig. 18, the spring 46^b is compressed and serves to 25 throw the shifter 46 to the right in Fig. 21, thus engaging clutch 39 with clutch 41 and causing the drum 44 and lower shaft 48 to rotate at the rapid speed of the upper shaft 7, whereby the cutter carrier frames 20 are 30 swung rapidly toward the work. The means for maintaining this rapid movement of the cutter carrier frames 20 toward the work and for stopping the same at the proper time will now be described with reference to 35 Figs. 38 and 39. Mounted on the end of the rod 60 is a block 59, which is in engagement with the lower end of a lever 58 pivoted in a recess in the work head 14 of the machine. The upper end of the lever 58, 40 as shown in Fig. 39, is provided with a V-shaped notch 58^a. When the rod 60 is thrown to the right by the engagement of the bolt 43 with the lever 61 in the manner described, the upper end of lever 58 is rocked to the left and the notch 58^a is engaged by a 45 V-shaped projection 57^b on the lower side of a longitudinally movable bolt 57, which is moved outward normally by means of a spring 57^a. The engagement of the projection 57^b with the notch 58^a holds the rod 60 50 in the position to which it has been moved by the lever 61, so that clutches 39 and 41 are held together and rapid movement is given to the cutter carriers. When, however, 55 the cutter carrier 19 in Fig. 39 is near to the stock, one of a series of pins 19^a on said carrier contacts with the outer end of rod 57 and pushes the same inward, whereby projection 57^b leaves the notch 58^a of lever 58, and a spring 61^a, which surrounds the 60 rod 60, forces said rod to the left in Fig. 18, whereby the tension exercised by arm 60^b on spring 46^b is released and the clutches 39 and 41 become disengaged, so that the 65 fast movement of the lower shaft 48 through

drum 44 is stopped and the carrier frames 20 are fed toward the work at the normal slow speed of the lower shaft 48. It will be understood that the spring 43' which backs the bolt 43 is stronger than the spring 70 46^b, which backs the bolt 45, so that the spring 43' will overcome the spring 46^b when bolt 43 is in contact with bolt 45, as previously described.

The devices for mounting and securing 75 the cutters in the chambers of the cutter-carrier or cylinder 19 are illustrated in Figs. 30 to 36. These devices permit the cutters to be shifted along the axis of their chamber to any position desired. The chambers 80 in the cylinder extend lengthwise of the same and open out at the end of the cylinder so that the cutters may be drawn out when detached or freed. The chamber is undercut, or is rather more than one half of a 85 circle in cross-section, and it extends to such a length that the cutter may be shifted along the same through the full operative or working space of the machine. Thus, where the cylinder has a plurality of chambers, the 90 several cutters therein may be set in different operative planes. For securing a cutter, 81, in place, it is mounted on a bolt, 78, having a conical part, 79, and on its end, a nut 80 (Figs. 30 and 31). The cutter or cutters, shaped as desired and of general ring-like form, are slipped on the bolt, on which is also slipped a securing collet 82, which fits normally rather snugly in the chamber in the cylinder and has in it a conical aperture 95 through which the coned part of the bolt passes. This collet is cut, as seen at 82^a in Fig. 32, so that it may expand on the bolt and thus fit tightly in the chamber when the coned bolt is driven into it by the nut. 100 Next to the nut is a coned collet 83, the cutters being embraced between these collets 82 and 83. This last named collet may be cut, as indicated in Fig. 36, or be left uncut. Figs. 30 and 33 show the cut, coned rings 105 84, which are slipped on the bolt and engage coned apertures in the cutters and the collet 82. When the assembled parts—as in Figs. 30 and 31—are slipped into the chamber in the cylinder 19 and the nut 80 110 screwed up the collet 82 will be expanded into the chamber in a manner to hold the cutters where set. By loosening the nut the cutters may be shifted in the chamber or wholly withdrawn. The ring-like cutter may also be slotted or cut radially so that it can expand. This is shown in Fig. 36. The turret 16 is, in itself, of substantially the usual construction, and its use will depend on the kind of work to be done. If the article 115 operated on is to be drilled axially, or otherwise so formed that the turret may be brought into play, the latter may be so coupled as to operate automatically; it is mounted to slide longitudinally of the ma- 120 125 130

chine, to and fro, for advancing to the work and receding therefrom, and is mounted to be rotated axially so as to bring different tools into play. Means to be hereinafter 5 described are provided whereby the turret, as it moves to and fro, operates the reversing mechanism so that in case it is cutting a screw, the article operated on may rotate backward in order to free it from the receding tap or die. The details of construction of the turret are to be seen in Figs. 10, 10, 14, 15, 16 and 17. The turret has any suitable number of holes or sockets arranged in pairs, and in rotating it makes at each 15 turn a part revolution. It is adapted to receive cutters, drills, taps, dies and other tools, the tool being held in place by a set-screw.

Fig. 17 is a dissected plan of the main slide 17, which carries the turret, the position of the latter being merely indicated by a circle in this figure. Fig. 14 is a sectional, fragmentary view of the slide in the same plane as the axis of the gage-wheel 65. Fig. 10 is a fragmentary section showing 25 the mechanism for operating the turret. Figs. 15 and 16 are a plan and end view of the lug-slide 68, detached.

On the cam-drum 44 (Figs. 18 and 20) are cams, 44^a, which impart the reciprocating movements to the main slide 17, engaging a lug 68^a on the lug-slide 68. This latter is mounted in the main slide 17, and a flange or part thereof is engaged by a rocking detent 67 (Fig. 14), this latter being 35 impinged upon by a spring-bolt 66 in the main slide. Under certain conditions this bolt is held against yielding, and this holds the detent 67 rigid so that the cams 44^a operate the main slide 17; but if the bolt 66 be left free to yield, the detent 67 will rock and the turret and its main slide will not be reciprocated. This regulation is effected by the gage-wheel 65, which has five radial 40 studs 65^b, and five depending studs 65^c in its underside. When one of the studs 65^c is in the path of the bolt 66, the latter cannot yield and holds the detent 67 against rocking; the lug-slide 68 then moves the main slide 17 and the turret. There is a 45 gage-stop 65^a on the frame and set in the path of the radial studs 65^b, so that, when one of these impinges on the stop the gage-wheel is rotated far enough to move the stud 65^c out of the path of the bolt 66 and 50 allow the lug-slide 68 to pass the detent 67 by rocking the latter. This leaves the turret stationary. A spring hook 68^b (Fig. 55 15) on the top of the lug-slide 68 engages the depending pins in the gage-wheel and 60 rotates it.

65^a is a frictional spring brake on the wheel 65 to prevent accidental rotation.

In the main slide 17 is a spring bolt 64, which enters a recess in a pendent flange on 65 the base of the turret and serves to lock it

against rotation and also to accurately position it. There is a cross lock-bolt 64^a behind the bolt 64, and these bolts are moved respectively by rockers 64^b and 64^c, which are themselves acted upon in succession by 70 a fixed block 64^d on the frame.

The turret is rotated by a rocker 18, mounted in the frame under the slide and backed by a spring 18^a, seen in Fig. 10. The nose or the upper end of this rocker engages one of any suitable number of depending studs 16^a on the turret and when the turret is moved with its slide the rocker-nose engages one of said studs and rotates the turret a part way around. When it is 75 desired to render the rocker inoperative, this is done by means of a manually operated crank-pin which engages a slot or recess 18^c in the rocker, seen in Fig. 10. It may be explained with respect to this figure, that the section through the main slide 17 is taken in the plane of the turret-axis while the section of the frame below is taken in the plane of the rocker 18. Hence the slot in the slide 17, in which the rocker 18 plays, 80 does not appear in Fig. 10, but is clearly seen in Fig. 17.

The reversing or shifting apparatus operated from the turret through the head 69 thereon, will now be briefly described by 85 reference to Fig. 1. The shifting rod 73, before mentioned, is coupled by a head 72, to a rod 70, 71 which extends through a guide at the point B, and through a guide at 69 on the turret. As the turret moves 90 forward, or toward the head 14, its guide 69 impinges on an adjustable stop-collar 70^a on 70, and shifts to reverse, and as the turret moves outward its guide ultimately 95 impinges on a similar stop-collar 70^b, and again shifts to go ahead. As the shift 100 requires considerable movement of the sliding rod, and as this must be effected quickly, there is spring plunger 74 in the head 14, which has pivotally mounted on its upper 105 end a finger 75, the upper end of the latter engaging the lower side of the rod 70. This device when carried a little beyond its center by the movement of the turret, suddenly acts 110 to shift the clutch-device, as will be readily understood. A set-screw 77 at B may be employed to hold the sliding rod in any position desired and a hand-lever 76 serves to 115 effect the reversing by hand if required.

It may be well to explain here how the 120 shaft 48 may be driven rapidly from the shaft 7, through the gear wheels seen at the right in Fig. 1, when the shaft 48 is driven normally from the worm 49. When the clutch-member 39 is made to engage with 125 the member 41 on the drum 44, thus coupling the latter to the shaft 7, a gear wheel 44^b on the drum drives through an intermediate 47^a, a spur wheel 47 on the shaft 48. (See Figs. 1 and 40). On this shaft 130

(at the left in Fig. 1) is keyed a spur wheel 48^a which gears with a pinion 48^b fixed to a stud wheel 48^c, this latter gearing with a pinion 48^d (Fig. 13) on a sleeve 63^e rotatable on the shaft 48. This sleeve carries one member (seen above in Fig. 11) of the slip-clutch 62, the other member of this clutch (seen below in Fig. 11) being carried by the worm-wheel 63, and backed by springs. 5 When the worm 49 is the driver the shaft 48 is driven slowly through the clutch, the sleeve and the gear-wheels described; but when the shaft 48 becomes the driver, the driven clutch-member slips over the other 10 and the worm-wheel 63 still rotates slowly. Referring to Fig. 21, when the member 39 is engaged with the member 40 the cutters are engaged with the member 41, the cutters are 15 disengaged and the parts are operating rapidly to get into position for the cutters to again operate.

At 85, in Figs. 1, 18 and 20, are seen gears for operating the drum 44 by hand, if required. The mechanism may be mounted 20 in any suitable frame 89, and there may be a tray or pan 90 to catch the oil which drips from the machine.

Respecting the operation of the jaws 29 which feed the stock through the spindle, 30 it may be stated that they have their fulcrum pivots disposed between their serrated faces and at their outer ends which keep them pressed yieldingly against the stock. 35 This causes the serrated faces to turn in a curve with a very short radius and effects a quick "bite" on the stock with very little lost motion.

The general operation of the machine will 40 be understood from the above description; but it will be proper to say that the operation will depend in a measure on the work to be performed. The purpose or object is to produce, automatically, with the machine 45 a number of like articles which may be turned from a rod of metal or stock, and cut off as finished. Suppose for example it is desired to produce a number of ornamental, turned articles, each two inches long, and 50 capable of being formed from a rod three-fourths of an inch in diameter. Suppose also that the design requires five cutters, set to operate successively along the two inches of length of the article. The machine is set 55 to operate as desired; the proper cutters are set in the cylinder 19; a bar or rod of stock is placed in each hollow spindle—if two spindles be used—and the machine set in motion. The stock is fed and clamped automatically; the cutters advance and make 60 the cuts, operating successively, the last one cutting off the finished piece. In this case the pawl 35^a at the friction box D, will be so set as to provide five operations of the

cutters to one operation of the feeding cam- 65 drum 9, as has been explained.

One characteristic of the present invention is the fixed head disposed between the two cutter cylinders, and the dies or work-supports 15, mounted in opposite faces of 70 the head. The head and work-supports extend the entire length of the working field or limits of the several cutters in the cylinders, so that however the cutters may be shifted in their chambers, or whichever cutter 75 may be put in operation, it will always bear on the stock at a point where the latter is backed by the work-support. This enables the machine to be employed on certain work which cannot be done where the stock being operated on projects beyond the support or head.

From inspection of the lower portion of Fig. 17, it will be seen that the block 65^a is secured by a bolt 65^f in an undercut slot 65^g, 85 so that by loosening the bolt 65^f, the block 65^a can be adjusted along the slot 65^g, whereby to rotate the wheel 65 at any desired point.

Having thus described my invention, I 90 claim—

1. In a forming machine, the combination with the cutter-cylinders and cutters, the operating cam, and the rocking frame carrying said cylinders and operated by said cam, of means for regulating the depth of the cut of the cutters, said means comprising a gage-wheel rotatively mounted in the frame carrying the cutters, and a hinged arm on said frame interposed between the 95 gage-wheel and the operating cam, substantially as set forth.

2. In a forming machine, the combination with the cutter-cylinders rotatively mounted in a rocking frame, the said frame, 105 the cutters in the cylinder, and the shaft and cam for feeding the cutters up to their work, of the hinged arm 20^c on the frame, the roller 20^b on said arm for the cam to bear upon, and the gage-wheel 86, rotatively mounted in the frame and provided with radial studs in its periphery, said studs being adapted to take behind and bear on the back of said hinged arm, substantially as set forth.

3. In a machine for the purpose specified, the combination with the cutter-cylinders and cutters, the rocking frame 20 in which said cylinders are mounted, the hinged arm 20^c, provided with a roller 20^b, 120 and the gage-wheel 86, provided with studs in its periphery, said wheel being mounted in the frame 20 and adapted by rotation to bring said studs to bear in succession on the back of the arm 20^c, of a rotating cam 125 adapted to bear on the roller 20^b for bringing the cutters up to their work, and automatic means for imparting intermittent ro-

tation to said gage-wheel, substantially as set forth.

4. A machine for the purpose specified, having two parallel spindles for carrying the stock, means for rotating said spindles and feeding the stock, a fixed head disposed within the space between the prolongations of the axes of said spindles, two work-supports mounted in the respective 5 opposite faces of said head, two cutter-carriers disposed opposite to the respective work-supports and movable up to and from the same, said work-supports extending throughout the entire working fields of the 10 15 said cutters, and means for moving the cutter-carriers up simultaneously to the work.
5. In a machine for the purpose set forth, the combination with a cutter-cylinder or holder having a chamber to receive a cutter, and the said cutter, of a conical bolt which extends through said cutter, an expanding collet on said bolt and occupying 20 said chamber, and a nut on said bolt.
6. In a machine for the purpose specified, 25 the combination with a cutter-cylinder or holder having in it a longitudinal open-ended chamber for the cutter extending throughout the operative space of the machine, of a cutter in said chamber, a tapered bolt which extends through said cutter, an expanding collet on said bolt to fit 30 in said chamber, conical friction collets to hold said cutter firmly on said bolt, and a nut on said bolt to draw the parts together.
- 35 7. A forming machine having two spindles for the stock abreast and at substantially the same level, two stock-feeding mechanisms, a fixed head disposed between the prolongations of the axes of the spin-

dles, hardened steel work-supports mounted 40 in the respective outer faces of said head, and two sets of cutters and their carriers disposed oppositely to the respective work-supports.

8. A forming machine having two spindles for the stock, abreast and substantially at the same level, oppositely facing work supports disposed between the prolongations of the axes of the spindles, two movable cutter carriers having cutters disposed opposite 45 50 the work supports, said work supports extending throughout the entire working fields of said cutters.

9. A forming machine having an adjustable cutter carrier, means for moving said 55 adjustable cutter carrier toward and from the work, automatic mechanism for operating said adjustable cutter carrier to bring different cutters into operative position, automatic means for moving said cutter carrier rapidly toward the work, and means operated by said cutter carrier for stopping said rapid movement.

10. An automatic screw machine having a 60 65 70 turret mounted upon a slide, a drum provided with permanent cams of uniform throw, and means intermediate the drum and the turret slide adapted to automatically interlock and release the turret slide at a predetermined point.

In witness whereof I have hereunto signed my name this 3d day of August, 1900, in the presence of two subscribing witnesses.

JAMES D. MATTISON.
